DEODORANT BLOCK SUPPORTING BASKET

Morris L. Weinstein and George L. Rosenberg, Atlanta, Ga., assignors to I. Schneid Inc., Atlanta, Ga., a corporation of Georgia

Filed May 2, 1967, Ser. No. 6,921

Term of patent 14 years

(Cl. D23—150)

FIG. 2 is a front elevational view of the deodorant block supporting basket shown in FIG. 1;

FIG. 3 is a rear elevational view of the deodorant block supporting basket shown in FIG. 1;

FIG. 4 is a side elevational view of the deodorant block supporting basket shown in FIG. 1, the other side being substantially complementary thereto; and

We claim:

The ornamental design for deodorant block supporting basket, substantially as shown and described.
